UNITED STATES PATENT OFFICE.

JOHN A. OLSON, OF CHICAGO, ILLINOIS, ASSIGNOR TO THE S-P MANUFACTURING COMPANY, OF CLEVELAND, OHIO, A CORPORATION OF OHIO.

MACHINE VISE.

1,416,970.

Specification of Letters Patent. Patented May 23, 1922.

Application filed March 29, 1919. Serial No. 285,992.

To all whom it may concern:

Be it known that I, JOHN A. OLSON, a citizen of the United States, residing at Chicago, in the county of Cook and State 5 of Illinois, have invented certain new and useful Improvements in Machine Vises, of which the following is a specification.

This invention relates to vises of the character commonly used in connection with 10 milling machines or other similar apparatus, and particularly to vises of this type which may be operated by air or fluid pressure.

The objects of the invention are, to provide 15 an improved type of milling machine vise; to provide a milling machine vise which is pneumatically operated; to provide a vise having a movable adjusting screw supporting member and means for actuating the 20 same; and, in general, to provide such an improved structure or apparatus as will be described more fully hereinafter.

In the accompanying drawings:

Figure 1 is a plan view of a vise embodying this invention;

Figure 2 is a longitudinal section taken on line 2—2 of Fig. 1;

Figure 3 is a cross section taken on line 3—3 of Fig. 1; and

Figure 4 is a cross section taken on line 4—4 of Fig. 1.

Milling machine vises such as are now in common use are usually provided with adjusting screw supports or bearings formed 35 integrally or rigidly with the base. In accordance with my invention, the adjusting screw support is made separate from the base and movable thereon, and suitable means are provided for actuating the support 40 in order to open and close the vise.

As shown in the drawings, a base or body portion 5 is provided, having any ordinary or preferred means for attaching the same to any suitable support, such as the table 45 of a milling machine or the like. This base is provided at one end with an upwardly extending jaw 6, having a false or work supporting piece 7 secured in position by means of screws 8. The base 5 is provided 50 with a guideway 9, on which a longitudinally movable jaw 10 is supported. This jaw has rectangular guides 11, which fit in grooves 12 in the base 5, and is held against the guideway or bed by means of screws 13, 55 which engage with guide straps 14 which

slide on the lower surface of the guideway. This jaw is also provided with a false jaw or work engaging piece 15, which is held by screws 16.

The jaw or slide 10 has a central threaded 60 hole 17 for the adjusting screw 18. The rear end of this screw is rotatably secured in a slide 19 and is held against longitudinal displacement in any suitable manner, as by means of pins 20, which engage with a circumferential groove 21 in the end of the screw. The screw 18 is also provided with a nut or turning portion 22, which abuts 65 against the face of the slide or screw driving head 19.

The slide 19 is mounted in a guideway 23 in the base 5, and is held by means of guide straps or plates 24 and screws 25 in a manner similar to the movable jaw 10. The slide 19 has a socket 26, which is preferably 70 formed by inserting a hardened semi-circular bearing 27, which bearing is held by screws 28. This socket serves for engagement with the end of a link 28, which, with the link 29, forms a toggle for actuating the 75 slide. These two links are pivoted together by means of a pin 30, which is preferably held in one member by having a driving fit, while turning freely in the other member.

The slide 19 is provided with a pin 31, 85 which engages with a hole in the link 28, the hole being slightly larger than the pin, so that the thrust will come against the socket bearing. Another pin 31' is secured 90 in the base 5 and serves as a bearing for the rear end of the toggle 29. The toggle is actuated by a cross-head or slide 32, which has a curved shoulder 33 adapted to push 95 against the inner ends of the toggle links during the pressure stroke. This block or slide is also provided with a pin 34, which engages with the opposite sides of the inner ends of the links for drawing the ends forwardly during the return or opening stroke. 100

The slide 32 may be actuated in any suitable manner, as by means of a piston rod 35, which is secured thereto, and is also secured to a piston 36 in the cylinder 37, this cylinder being provided with any ordinary or preferred forms of intakes and outlets and means for controlling the air or fluid thereto (not shown).

When the piston 36 moves forwardly from the position shown in Fig 1, the pin 34 in 110

the slide 32 will pull the inner ends of the toggle links forward and thereby cause the pin 31 to move to the left, and will draw the slide 19 to the left, causing the jaws 5 to be opened. When the work piece has been inserted between the jaws, air is admitted to the cylinder 37, causing the piston to move backwardly and the shoulder 33 on the slide or cross-head 32 will press 10 against the adjacent ends of the toggle links, and will straighten out the toggle, thereby forcing the slide or screw driving head 19 to the right, causing the jaws to tighten on the work piece. It will, of course, be apparent that the screw 18 may be turned to 15 adjust the jaws for different sized work pieces, so that if considerable pressure is desired, the toggle links should be approximately in alignment in order to exert the 20 greatest clamping force when the jaw 10 reaches the end of its movement.

While the present illustration shows a practical and preferred embodiment of this invention, it will be apparent that the pneumatic cylinder may be arranged in different positions and other operative connections made for actuating the toggle and the device may be made in different sizes in order to provide for different kinds of work, 30 and the shape and details of construction may be varied without departing from the scope of this invention as defined by the appended claims.

Having thus described my invention, 35 what I claim is:

1. In a vise, the combination of a support having a fixed jaw extending upwardly

therefrom, a slideway in said support, a 40 slide mounted in said slideway, a screw rotatably secured to said slide and engaging with a threaded hole in said slide, a toggle connected with said slide for actuating the same, and means for actuating the 45 toggle.

2. The combination with a base having a fixed jaw at one end, of a slide, a 50 slideway in said base, a screw rotatably mounted in said slide and engaging with a threaded hole in the slide, a pin in said base at the rear of the 55 slide, a toggle connected with said pin and said screw, a cross-head mounted in said base and engaging with said toggle, and a fluid pressure device for moving said cross-head.

3. In a device of the character set forth, the combination of a support, a slide 60 movably mounted on said support, power actuated means for moving said slide, a slide, a 65 adjustable connection between said slide and said jaw, and a fixed jaw cooperating with said slide.

4. In a machine vise, the combination of 70 a support having a fixed jaw thereon, a slide movably mounted on said support, a jaw movably mounted on said support and coacting with the first named jaw and an adjusting screw coacting with the slide and the 75 slide for adjusting the distance between them.

JOHN A. OLSON.
